UNITED STATES PATENT OFFICE.

WILLIAM J. MITCHELL, OF KOPIAH, WASHINGTON.

MINER'S ACETYLENE LAMP.

Application filed May 13, 1922. Serial No. 560,557.

To all whom it may concern:

Be it known that I, WILLIAM J. MITCHELL, a citizen of the United States, residing at Kopiah, in the county of Lewis and State 5 of Washington, have invented certain new and useful Improvements in Miners' Acetylene Lamps, of which the following is a specification, reference being had to the accompanying drawings.

10 This invention relates to acetylene lamps which are used by miners, and particularly to that type of lamp wherein there is an upper water containing chamber, a lower carbide containing chamber, and means 15 whereby water may be caused to flow from the upper chamber into the lower chamber to cause the generation of gas in the lower chamber.

One of the objects of the present invention is to provide means whereby the carbide containing chamber may be cleared of used carbide whenever desired, and more specifically to provide means whereby the sludge may be pulled out of the chamber without 25 the necessity of breaking up the carbide and disfiguring or deforming the carbide chamber in so doing.

Still another object is to provide improved means whereby to control the flow 30 of water from the water chamber to the carbide chamber.

Another object is to provide means whereby if the gas jet be blocked up for any reason the gas will come back through the 35 water feed and be discharged into the open air, the gas being separated from the water and the water being returned to the water chamber instead of running down onto the miner's face.

Another object is to provide means for 40 supporting a pad of cotton in position across the duct leading to the gas jet to thereby filter the gas passing to the jet.

A still further object is to improve upon 45 the closure whereby water is admitted to the water containing chamber.

Other objects will appear in the course 50 of the following description.

My invention is illustrated in the accompanying drawings, wherein:—

Figure 1 is a rear elevation of a miner's lamp constructed in accordance with my invention;

Figure 2 is a vertical section therethrough 55 from front to rear;

Figure 3 is a front elevation;

Figure 4 is an enlarged fragmentary front elevation partly in section;

Figure 5 is an enlarged vertical section of members 43 and 49;

Figure 6 is a top plan view of the lamp.

Referring to these drawings, it will be seen that I have illustrated a miner's lamp comprising a water containing chamber, designated 10, and having integrally formed therewith the cylindrical carbide containing chamber 11. The water containing chamber is illustrated as being approximately rectangular in form and having a back wall 12 and a front wall 13. Water may be 60 poured into the water containing chamber 10 through the opening 14, this opening being shown as rectangular in section and having inwardly extending side walls 15 and upwardly extending end walls 16, there being a slide 17 adapted to close this opening and sliding between the walls 15. It will be seen that immediately over the opening the walls 15 are turned acutely inward so that as the sliding cover is moved forward, it will be forced down upon its seat to prevent any chance of water leaking out. The cover cannot come off or become lost and at the same time it is relatively easily 65 opened.

Extending upward from the carbide containing chamber or gas generating chamber 11 is a gas duct 18 which extends upward in front of the wall 13 and then outward where it is provided with a gas jet opening 70 19 of any suitable character. The outer face of the wall 13 constitutes a reflector and the side and top wall of the chamber 10 extend on beyond this reflector so as to form a hood 20.

For the purpose of igniting the jet, I provide a plunger 21 which extends up through the top of the hood and has a knob at its upper end, the lower end of the plunger extending downward through the bottom of 75 the hood. The middle portion of the plunger is formed to provide a plate 22 toothed on one edge, as at 23, these teeth extending upward. The plunger is urged upward by a spring 24 which surrounds the lower portion of the plunger and engages against the plate 22 or any other suitable abutment, and at its upper end engages against the middle portion of the plunger. Coacting with the plate 22 and constituting a guide for the 80 plunger is a cleft member 25, in the cleft of which the plate 22 reciprocates. This

cleft member has its outer end screw-threaded, as at 26, and is formed inward of this screw-threaded portion 26 with a shoulder 27 within which is disposed a piece of flint 5 28. This flint is urged inward against the teeth 23 by means of a spring 29. An adjusting cap 30 engages the screw-threads 26 and bears against the outer end of the spring 29. By rotating this cap, the tension 10 on the spring may be increased and the flint forced with greater or less force against the teeth 23. Obviously, when it is desired to ignite the gas it is only necessary to depress the plunger quickly one or twice and a 15 stream of sparks will spring from the flint 28, which will cause the ignition of the gas.

The bottom of the carbide chamber 11 is formed by a plate or disk-like cover 31. This is hinged, as at 32, to the flange 33 at 20 the lower end of the chamber 11 and is formed to provide a seat 34 for a gasket 35. The flange 33 is formed at one point to provide a seat or shoulder 36. Pivottally connected to the under face of the cover 31 25 is a link 37 which is angular in form so that it may swing down beneath the cover or be brought up approximately parallel to the side wall of the chamber 11. To the cross bar of this link is pivoted the shank 38 of a hook 39. This shank is pivoted to the link 37 at 40 and extends below this point of pivotal engagement. If it be desired to close the cover and hold it locked, the lower end of the shank is engaged with 35 the shoulder 36 and the shank turned up to a vertical position. This draws upon the link 37 and locks the cover tightly in place. The shank moves toward the wall of the chamber 11 sufficiently far so that strain on 40 the cover will not act to open the shank. The upper end of the shank is engaged between two spring clips 41 so that the shank will not accidentally come out of position. The hook 39 forms the means whereby the 45 lamp is hooked in the miner's cap and at the same time forms a cam which will draw the cover positively in place, and also forms a lever for opening the cover against any adhesion, and which will break any adhesion 50 between the cover and the flange 31, and forms a convenient handle whereby the cover may be manipulated.

Extending upward through the web 42 which forms the bottom of the water chamber 10 and the top of the carbide chamber 11 is a tube 43 formed at the level of the web 42 with a valve seat 44. Below this point the tube 43 is perforated at a plurality of points and at its extreme lower end, 55 as at 45. Just above the web 42 the tube 43 is perforated, as at 46. Above these perforations 46 the tube is imperforate nearly to its upper end. Adjacent its upper end, however, it is provided with overflow openings 47. Disposed on the seat 44 is a ball 60

valve 48 which may be made of a steel ball such as used in ball bearings, and for the purpose of depressing this valve I provide a tubular hollow member 49 screw-threaded at its upper end to engage with a screw-threaded opening 50 in the top of the water chamber. Above the top of the water chamber this tubular member 49 is provided with a handle 51 and there is an opening 52 leading out from the interior of the tubular member 49 through this handle to the exterior air. This member 49 is of such length that when it is screwed down it will engage the ball 48 and hold it tightly to its seat and this member may be screwed upward to any desired distance within a certain range from the ball 48 to release the pressure upon the ball and permit the leakage of water from the water chamber past the ball 48 into the carbide chamber. This member 49, as before remarked, is tubular and provided with a plurality of perforations 53 which afford means, as will be later described, for the separation of the water 80 from the gas. 90

Disposed below the entrance to the duct 18 is a resilient pad holder 54 for the support of a cotton pad just below the lower end of the duct 18. This cotton pad only need be renewed once in a while and may be 95 very readily pulled out of the holder and put back in place. The holder is so constructed as to afford marginal flanges extending over the pad.

In miners' lamps of the character described, carbide is liable to collect and coagulate in the carbide chamber and it is rather difficult to get the carbide out. Carbide hardens within the chamber and then the usual practice is to bang the lamp or carbide chamber against some body to loosen the carbide, or insert an implement into the chamber to loosen it. This tends to deform or bruises the lamp and may put its gas regulating mechanism out of order. 100 In order to avoid the necessity of so treating the lamp, I provide a carbide cleaner which consists of a circular disk 55, the outer margin of this disk being downwardly turned and toothed, as at 56, this disk being attached to a tubular handle 57 having a button or head 58 at its lower end. The disk 55 has a central opening 59 which is in alignment with the bore of the tubular handle 57 and of a size to loosely surround and fit over the downwardly extending portion of the tube 43. The tubular handle 57 is longer than the lower portion of the tube 43 so that flow through the tube 43 is not obstructed in any manner. The 105 tubular handle 57 has its side apertured, as at 60, at a plurality of points. Water flows down past the valve 48 and through the lower portion of the tube 43 and out through the openings 45 and then out 110 115 120 125 130

through the openings 60 into the carbide chamber. This tubular handle 57 prevents the blocking up of the openings 45 and thus keeps the water tube clean. Furthermore, it constitutes a means whereby the used carbide may be readily removed from the carbide chamber. When it is desired to remove the carbide, the closure to the chamber is opened and the operator takes hold of the button 58 and pulls the cleaner out of the chamber, pulling the carbide with it. The teeth in the false bottom 55 provide means whereby any coagulated carbide may be broken up by rotating or otherwise operating this disk or false bottom 45, which will cause the teeth to saw against the carbide.

In order to fill the chamber with carbide, the lamp is turned upside down, then the shank of the hook 39 is pushed out with the thumb or fingers until it passes the center, and then the bottom of the lamp will fly open. The button at the end of the carbide chamber is then used to lift the carbide cleaner and used carbide out. The used carbide is detached from the carbide cleaner, then the carbide cleaner put back in place, the fresh carbide is filled into the carbide chamber, and then the hook is put back with the adjacent end of the hook shank resting upon the shoulder 36 and the hook turned into a position parallel to the axis of the lamp, which locks the bottom in place and closes the carbide chamber entirely.

In other miners' lamps known to me, the carbide chamber is closed by a screw bottom. The carbide gathers around the threads of this screw bottom, making it extremely hard to unscrew the bottom and necessitating sometimes the use of a wrench. Even then it often occurs that the bottom will not come out and it is necessary to pound against the bottom, which causes the bottom to leak. All of these inconveniences are entirely obviated by the improved closure which I have provided.

In order to operate this device, when a charge of carbide and water is in the lamp, the head 51 is turned to the left once or twice, which lifts the member 49 off from the ball 48 and allows certain freedom of the ball and allows the water to leak around it and down into the carbide a drop at a time. When the valve is screwed down tight, however, the ball seats in the tube below the entrance for the water, and the water is then shut off from the carbide. The tubular member 49 not only constitutes a means whereby the valve 48 may be held to its seat or may be permitted to rise, but it also constitutes a gas and water separator when the gas jet is blocked up. Under these circumstances, the gas comes back through the water feed and is forced through these small openings 53 into the in-

terior of the member 49 and then out through the opening 52, while the water runs back into the water chamber through the overflow openings 47 instead of running down onto the miner's face. The perforation 52 also constitutes means whereby to permit the inlet of air to the lamp.

The operation of the igniter is obvious. The plunger 41 is forced downward as far as it will go and then it is released and the spring 24 will push the plunger up quickly. This quick motion makes a sure spark. The adjusting nut 39 should not be adjusted up too tightly, as the flint will cause too much friction on the plunger. I am aware that miners' lamps are usually provided with wheel lighters, that is with a toothed wheel against which the flint bears and which is operated by rotating the wheel by means of the thumb. This is objectionable because if a miner's hands be wet or if there is oil on them, he clogs up the teeth of the wheel and then cannot strike a light from the flint. This is quite an important feature of the lamp, inasmuch as oftentimes a lamp goes out just as the miner has lighted his fuses. He may have no matches and may be depending entirely on the lamp for his lighting, and being unable to light the lamp may cause a very bad accident. This plunger does away with trouble of this kind, inasmuch as the miner's fingers do not come in contact with the teeth which operate the plunger flint. In lighting this lamp, the palm of the hand is held over the front of the reflector so that the gas coming through the jet will collect within the reflector. Then the plunger is pushed down and released and the gas will ignite. By this means the lamp may be lighted in a very strong current of air. This manner of lighting the lamp would, of course, be impossible where it is necessary to rotate a milled igniting wheel, as is the case with ordinary miners' lamps known to me.

It will be noted from Figure 2 that the disk 55 is disposed immediately beneath but spaced from the filtering pad 54 so that this disk will permit the passage of gas around it, will prevent the filtering pad from becoming blocked by carbide or sludge so that the gas may pass freely through the filtering pad at all times. Furthermore, the tubular perforated handle 57 of the cleaning disk forms a shield around the perforated tube 47 and prevents the carbide from packing around and closing the perforations 45 in the tube so that the water has every chance to pass the perforations and come in contact with the carbide. Furthermore, it will be seen in that with this construction the carbide never comes in contact with the inner perforated tube so that this inner tube is always clear and clean, and when the handle 57 is withdrawn the

cleaner carries all the sludge and used carbide out of the generating chamber, and it will be only necessary under certain circumstances to clean the handle 57 and open 5 the perforations in the handle which, because the cleaner is entirely removed from the generating chamber, can be easily done. There will be no necessity of cleaning, however, the tubular member 43 nor opening 10 the perforations therein.

The valve 48 is disposed within a basin-shaped seat which is larger in diameter than the valve so that the valve can more or less roll within this seat. Inasmuch as the lamp 15 is carried in a miner's cap, it follows that every time the miner moves his head the ball valve 48 will roll from its seat to some extent, thus unseating the ball and permitting water to trickle down and through the 20 openings 45 and so into contact with the carbide. Thus there is a more or less constant feed of water through the carbide. By turning down upon the stem 49 this ball may be held firmly upon its seat.

25 While I have illustrated a form of my device which I have found to be thoroughly practical and which is particularly effective, I do not wish to be limited thereto, as it is obvious that many changes might be 30 made in the details of construction and arrangement of parts without departing from the spirit of the invention.

I claim:-

1. An acetylene gas generator including a 35 water chamber and a carbide chamber separated from each other by a web, a tubular member extending longitudinally through the web and formed adjacent the web with a basin-shaped valve seat, a ball valve dis- 40 posed in said seat and freely movable therein, the tubular member above said valve being provided with water inlet openings and below the valve being perforated, and means 45 passing through the upper end of the tubular member and through the top of the water whereby the valve may be held to its seat or released.

2. An acetylene gas generator including a 50 water chamber and a carbide chamber separated from each other by a web, a tubular member extending longitudinally through the web and formed adjacent the web with a basin-shaped valve seat, a ball valve resting upon the basin-shaped seat and freely mov- 55 able in all directions thereon, the tubular member above said valve being provided with water inlet openings and below the valve being perforated, and a member hav- 60 ing screw-threaded engagement with the top of the water chamber and extending downward through said tubular member and adapted to bear against said valve and hold it to its seat or to be released from engagement with the valve.

65 3. An acetylene gas generator including a

water chamber and a carbide chamber separated from each other by a web, a tubular member extending longitudinally through the web and formed adjacent the web with a basin-shaped valve seat, a ball valve resting 70 upon the seat and freely movable in all directions thereon, the tubular member above said valve being provided with water inlet openings and below the valve being perforated, and a tubular member having screw- 75 threaded engagement at its upper end with the top of the water containing chamber and extending down into the first named tubular member and adapted to bear against the valve, this inner tubular member being per- 80 forated and having a vent opening to the exterior air.

4. A gas generator including a carbide containing chamber, a closure for the bottom of the chamber, and means for removing the 85 carbide from the chamber comprising a disk-like member having a serrated flange and normally disposed adjacent the top wall of the chamber and having a depending handle whereby it may be removed from the 90 chamber.

5. An acetylene gas generator including a gas generating carbide containing chamber having a closure at its lower end, a duct leading from the upper end of the chamber, 95 a filtering member disposed beneath the lower end of the duct, and a cleaner comprising a disk adapted to be disposed within the carbide containing chamber adjacent the top thereof and below the filtering member, 100 and a handle extending toward the closure whereby the cleaner may be removed, the disk being so formed that the gas may have access to the filtering member.

6. An acetylene gas generator including a 105 water containing chamber and a subjacent carbide chamber, a tubular member extending from the water containing chamber into the carbide chamber and perforated within the water containing chamber and the carbide chamber, an annular disk-like cleaner disposed within the carbide chamber adjac- 110 ent the upper end thereof and having a per- 115forated tubular handle normally surround- 120 ing the tubular member that is within the carbide chamber, the tubular handle of the cleaner permitting its removal and acting as a shield for the perforations of the tubular member.

7. In an acetylene gas generator, a water- 125 containing chamber and a subjacent carbide chamber, a perforated tubular member ex- 130 tending from the water-containing chamber into the carbide chamber, the tubular mem- 135 ber adjacent the bottom of the water-con- taining chamber being formed to provide a valve seat, a valve coacting therewith, and a stem separate from the valve and extending downward through the top of the water- containing chamber and into said tubular 130

member and adapted, when shifted downward, to hold the valve to its seat but when raised permitting the valve to rise.

8. In an acetylene gas generator, a water-containing chamber and a subjacent carbide chamber, a perforated tubular member extending downward from the upper portion of the water-containing chamber into the lower end of the carbide chamber, said member at the lower end of the water-containing chamber being formed with a basin-shaped valve seat, a ball valve loosely resting upon said seat but freely movable in all directions thereon, and a stem extending downward from the top of the water-containing chamber through the upper portion of the tubular member and having screw-threaded engagement at its upper end with the top wall of the water-containing chamber whereby said stem may be turned to bring it into engagement with the valve but hold it to its seat or turned away from the valve to permit the oscillation of the valve.

9. In an acetylene gas generator, a water-containing chamber and a subjacent carbide chamber, a perforated tubular member extending downward from the upper portion of the water chamber into the lower end of the carbide chamber, said member at the lower end of the water-containing chamber being formed to provide a valve seat, a valve coacting therewith, a tubular stem extending downward through the top of the water-containing chamber, through the upper portion of the tubular member, and having screw-threaded engagement at its upper end with the top wall of the water-containing chamber whereby said stem may be turned to bring it into or out of engagement with the valve, said stem being hollow and perforated and having an air vent at its upper end.

In testimony whereof I hereunto affix my signature.

WILLIAM J. MITCHELL.
